(57) **CLAIM**

The ornamental design for a shoe with decorative sole, as shown and described.

DESCRIPTION

FIG. 1 is a bottom perspective view of the shoe with decorative sole in accordance with my new design;

FIG. 2 is a bottom plan view thereof;

FIG. 3 is a top plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The broken lines in FIGS. 1-7 are for purposes of illustrating portions of the shoe with decorative sole that form no part of the claimed design.
